(57) **CLAIM**

The ornamental design for a foot step for heavy duty trash can as shown and described.

DESCRIPTION

FIG. 1 is a top perspective view of a heavy duty trash can with foot step showing our new design;

FIG. 2 is a bottom perspective view thereof;

FIG. 3 is a front elevational view thereof;

FIG. 4 is a top plan view thereof;

FIG. 5 is a top plan sectional view thereof taken along the plane of line 5-5 of FIG. 3;

FIG. 6 is a bottom plan view thereof; and,

FIG. 7 is a left-side elevational sectional view thereof taken along the plane of line 7-7 of FIG. 3, the right-side being a mirror image.

The broken lines in the drawings depict portions of the heavy duty trash can with foot step that form no part of the claimed design.

The long and short broken lines shown in FIG. 3 indicate cross-sectional lines that form no part of the claimed design.
